HIS ATTORNEY

UNITED STATES PATENT OFFICE.

CHARLES E. PUTMAN, OF PORTLAND, OREGON.

IMITATION SHAKE SHINGLE.

Application filed September 24, 1924. Serial No. 739,630.

To all whom it may concern:

Be it hereby known that I, CHARLES E. PUTMAN, a citizen of the United States, and a resident of Portland, in the county of

5 Multnomah and State of Oregon, have invented a new and useful Imitation Shake Shingle, of which the following is a specification.

This invention relates generally to the 10 wood shingle industry and particularly to the making of ornamental shingles in imitation of the old time split shingles known as shales.

The principle object of my invention is 15 the production of a wooden shingle having the appearance of a split shake when laid and yet giving all of the warmth usually obtained from sawed shingles and at the same time capable of being laid with no 20 greater difficulty than is the sawed shingle.

I accomplish these results in the manner set forth in the following specification and illustrated in the accompanying drawing, in which—

25 Figure 1 is a side elevation of a rafter with roof boards and shingles placed thereon.

Figure 2 is a plan of Figure 1.

Figure 3 is a longitudinal section through 30 a shingle of which Figure 4 is a plan and Figure 5 is an end view from the butt end of the shingle.

Referring in detail to the drawing, I have 35 illustrated my product in its preferred form which is similar to an ordinary sawed shingle of varying dimensions to suit the individual requirements. This shingle has the usual tapering body 10 whose butt 11 is considerably thicker than is its tip 12. In 40 practice these shingles range in length from 1 to 3 feet and are laid somewhat less than half of their length to the weather. The weather portion of the butt end of the shingle contains the novel feature of my invention as this portion is treated in a manner to produce the wavy fluted or grooved effect common to split shingles.

It will be observed that the grooves 13 are cut along a line approximately midway be-

tween the upper side of the shingle and its 50 under side 14 although this is not necessarily the case. In some instances the bottoms of the grooves may be parallel to the upper side of the shingle and in other instances they 55 may be parallel to the under side depending upon various factors. The usual roof boards 15 and rafters 16 are employed.

As previously stated the principal idea in making the present invention was to secure the much desired appearance of a shake roof 60 or to improve upon such appearance while at the same time avoiding the several important attendant drawbacks present with the old form, namely, the difficulty in laying the shingles without breaking them and 65 the entire inability to keep out the air currents since the grooves in the split shingles necessarily extended the entire length of the top surface.

In practice the shingles which are very 70 much larger than shingles common in the East, are sawed in the ordinary manner forming a smooth plane tapered shingle which is then passed under a battery of saws or cutters adapted to produce a wavy effect 75 to that portion of the surface of the shingle which is to be exposed to the weather, as best seen in Figure 5 wherein there are a half a dozen troughs and crests making a wavy effect in which the waves are quite 80 shallow in height but are quite wide transversely to the shingle length.

I prefer that the larger waves be grooved by a plurality of rather slight grooves running the entire extent of the waves and of 85 course parallel to the long side of the shingle as are the waves themselves. The grooving of the waves increases the beauty of the shingle.

I am aware that many attempts have been 90 made to produce imitation shake shingles experimentally such as ripping a split shake of double thickness which provides little improvement over the ordinary shake.

I therefore do not claim such devices 95 broadly but I do intend to cover all such forms and modifications thereof as fall fairly within the appended claims.

I claim:

1. A tapered shingle having a plane back and a face plane toward the upper or thin edge of the shingle and fluted in smoothly curved waves thruout the exposed area toward the thick edge, whereby the thicker portions when laid as a roof or wall will simulate shake shingling and the thinner portions will insure airtightness.

2. A tapered shingle having a plane back ¹⁰ and a face plane toward the upper or thin edge of the shingle and fluted in shallow wide waves thruout the exposed area toward the lower or thick edge, each of said waves being cut by a plurality of slight parallel ¹⁵ grooves.

CHARLES E. PUTMAN.
